The ornamental design for a swing with flags, as shown and described.

DESCRIPTION

FIG. 1 is a front perspective view of a swing with flags according to the present invention.

FIG. 2 is a side elevation view of the swing with flags illustrated in FIG. 1.

FIG. 3 is another side elevation view of the swing with flags illustrated in FIG. 1

FIG. 4 is another side elevation view of the swing with flags illustrated in FIG. 1.

FIG. 5 is another side elevation view of the swing with flags illustrated in FIG. 1.

FIG. 6 is a top plan view of the swing with flags illustrated in FIG. 1; and,

FIG. 7 is a bottom plan view of the swing with flags illustrated in FIG. 1.

The broken lines depict features of the swing with flags that form no part of the claimed design.
